United States Patent Office

Des. 232,979
Patented Sept. 24, 1974

232,979

FABRIC FOR CURTAINS

Peter Schroeder, Arni-Islisberg, Switzerland, assignor to Gardisette International AG, Lucerne, Switzerland

Filed Mar. 30, 1971, Ser. No. 129,650

Claims priority, application West Germany Oct. 6, 1970

Term of patent 14 years

Int. Cl. D5—05

U.S. Cl. D92—1 PP

The drawing is a front elevation view of a curtain fabric showing my new design, the design is shown over a dark background for purposes of illustration, the top being an indeterminate length of plain unornamented net extending to the top selvedge.

I claim:

The ornamental design for a fabric for curtains, as shown and described.
